UNITED STATES PATENT OFFICE.

OTTO C. GRUTTER, OF CRESTON, ILLINOIS.

WATER-HEATING APPARATUS.

Application filed February 23, 1922. Serial No. 538,482.

My present invention relates to what is commonly called a hot water coil of a furnace and among the objects thereof are to get as much of the body of the heating apparatus as possible down in the furnace to a point where it will be in close proximity to the fire; to so shape the heating apparatus that it may be placed at one side of the furnace, out of the way when fuel is being put in, and yet the same will be sufficiently long to secure the proper amount of heat absorbing surface; to provide a device of the character described with openings for the convenient introduction and use of a brush or the like for removing scale from the interior of the apparatus; and such further objects, advantages and capabilities as will later more fully appear.

My invention further resides in the combination, construction and arrangement of parts illustrated in the accompanying drawings, and while I have shown therein a preferred embodiment, I desire the same to be understood as illustrative only and not as limiting my invention.

In the annexed drawings,

Fig. 1 is a perspective view of my new apparatus, showing the same applied to a furnace.

Fig. 2 is a sectional plan view of Fig. 1.

Fig. 3 is an elevation of my new heating apparatus.

Fig. 4 is a sectional elevation substantially along the plane indicated by the line 4—4 Fig. 5.

Fig. 5 is a longitudinal section of the construction shown in Fig. 3.

Fig. 6 is an end view of this construction.

Referring more in detail to the annexed drawings, numeral 1 designates in general a furnace provided with an opening for a door as customary and preferably having an off-set portion 2 for the accommodation of the heating apparatus 3, together with its feed and return pipes 4. This offset portion 2 also functions as a support for the heating apparatus 3.

The heating apparatus 3 comprises essentially two substantially horizontal main parts 6 and 7 connected by a downwardly inclined part 8. This member 8 carries the body of the heating apparatus to a point where it is in such close proximity to the fire that it will get the maximum amount of heat. This member 8 does not go below the fuel line and therefore it

saves wear and tear of actual contact with the fuel and receives an adequate proportion of heat. The inner portion of this heater is bent inward laterally in a substantially horizontal direction to form the part 9, curved into substantial conformity to the interior wall of the furnace. Extending substantially centrally of member 3 and longitudinally thereof, is a partition wall 10 which divides this member into two channels, one connected with a water supply pipe and the other with a water return pipe. It will therefore be understood that the heat of the fire will be absorbed by the casting and transmitted to the water inside of the same, which water is then heated and rises to the upper channel 12 through which it flows, being ordinarily delivered to a hot water tank adjacent the furnace, though of course, this is not essential as the hot water may be delivered to any point desired. As the water flows out through channel 12, cool water is supplied through channel 13 to be in turn heated.

On the inner face of member 3, where they will be most fully exposed to the heat of the furnace fire, are a plurality of bosses 14, cast integral with the inner face of the heating coil. Being cast solid, these members have not an internal cavity for the collection of scale which would reduce the heating efficiency of the bosses. These bosses therefore present a large amount of additional surface for the absorption of heat which is transmitted to the water flowing through the apparatus to heat the same. In order to make it possible to remove any scale which may collect on the interior of the heating member, openings 15 and 16 are provided, which openings are closed by means of plugs 17. Upon removal of the plug 17 from opening 15, a wire brush or the like may be inserted and passed into either channel 12 or channel 13 for scratching from the walls thereof any scale or other foreign matter which may have collected thereon. It is also possible to remove plug 17 from opening 16 and pass such a brush into channel 13 for removing scale from the walls thereof. With the pipes 4 removed from the outer end of member 3 it is also possible to insert a brush into the openings in this end of the structure and clean out the outer end of channels 12 and 13.

It is of course understood that the specific

description of structure set forth above may be departed from without departing from the spirit of my invention as set forth in this specification and the appended claims.

5 Having now described my invention, I claim:—

10 1. A water heating apparatus comprising a conduit having two ports at one end thereof, one port for receiving a cold water pipe and the other for a hot water pipe, a longitudinal partition in said conduit separating the two ports and forming two channels extending to the opposite end of said conduit, the channels being connected at a position remote from the said ports, the conduit being downwardly curved in a portion intermediate its ends and having a corresponding reverse curve to thereby dispose the two end portions of the conduit substantially in 15 parallel horizontal planes, the downwardly curved portion having a clean-out port positioned to permit the insertion of a clean-out implement longitudinally of said portion.

20 2. A water heating apparatus for insertion into a furnace comprising a conduit having a port at one end thereof for communicating with a cold water pipe and another port in the same end for communicating with a hot water pipe, a longitudinal partition within said conduit separating said ports and extending toward the other end of said conduit, the outer end of said conduit being adapted for resting on the bottom of a fire box door opening, the next inner portion of 25 the conduit being curved downwardly to dispose the innermost end of the conduit at a level below the outer end, said curved portion having a port so disposed as to permit of the insertion of a clean-out implement longitudinally of said portion.

30 3. In a water heating apparatus, water supply and return pipes adapted to lead into a furnace, a heating member connected thereto and adapted to fit near one side of a furnace fire box, said member curving downwardly to have the inner portion below the level of the bottom of the furnace door, a clean-out port in the downwardly curved portion and the inner end curving laterally to 35 approximate the wall curvature of the fire box, said heating member having an internal position throughout the major portion of its length dividing the interior thereof into two channels, and an aperture at the inner extremity of the inwardly curved portion for the insertion of a clean-out implement to clean either of said channels.

40 4. A water heating apparatus for insertion into a furnace comprising a conduit having a port at one end thereof for communicating with a cold water pipe and another port in the same end for communicat-

ing with a hot water pipe, a longitudinal partition within said conduit separating said ports and extending toward the other end of said conduit, the outer end of said conduit being adapted for resting on the bottom of a fire box door opening, the next inner portion of the conduit being curved downwardly to dispose the innermost end of the conduit at a level below the outer end, said curved portion having a port so disposed as to permit of the insertion of a clean-out implement longitudinally of said portion, the innermost portion of the conduit being curved to approximate the curvature of the inner fire box wall, the sides of the conduit nearest the furnace wall being smooth and the side nearest the fire being provided with heat absorbing bosses.

45 5. A water heating apparatus for insertion into a furnace comprising a conduit having a port at one end thereof for communicating with a cold water pipe and another port in the same end for communicating with a hot water pipe, a longitudinal partition within said conduit separating said ports and extending toward the other end of said conduit, the outer end of said conduit being adapted for resting on the bottom of a fire box door opening, the next inner portion of the conduit being curved downwardly to dispose the innermost end of the conduit at a level below the outer end, said curved portion having a port so disposed as to permit of the insertion of a clean-out implement longitudinally of said portion, the extremity of the innermost portion of the conduit having a clean-out port so disposed as to permit of the insertion of a clean-out implement above and below the partition without removing the apparatus from the furnace.

50 6. In a structure of the character described, a heating apparatus partitioned into two channels, one carrying water supply pipe, and the other water return pipe, said heating apparatus adapted to fit near one side of a furnace fire box, a downwardly inclined portion of said apparatus connecting a third portion of said apparatus substantially parallel with the first portion, said third inner portion curving laterally to approximate the wall curvature of the fire box, said heating member having in one wall of the downwardly curving portion an aperture for the insertion of a clean-out implement, and a plug to close said aperture and solid heat absorbing bosses on the face of the heating member.

55 In witness whereof, I hereunto subscribe my name to this specification.

OTTO C. GRUTTER.

CERTIFICATE OF CORRECTION.

Patent No. 1,628,664.

Granted May 17, 1927, to

OTTO C. GRUTTER.

It is hereby certified that error appears in the printed specification of the above numbered patent requiring correction as follows: Page 2, line 52, claim 3, for the word "position" read "partition"; and that the said Letters Patent should be read with this correction therein that the same may conform to the record of the case in the Patent Office.

Signed and sealed this 7th day of June, A. D. 1927.

Seal.

M. J. Moore,
Acting Commissioner of Patents.
